UNITED STATES PATENT OFFICE.

EPHRIAM J. SCOTT, OF PROVIDENCE, RHODE ISLAND.

MACHINE FOR OPENING ENVELOPS.

1,143,919.

Specification of Letters Patent. Patented June 22, 1915.

Application filed July 2, 1913. Serial No. 776,913.

To all whom it may concern:

Be it known that I, EPHRIAM J. SCOTT, a citizen of the United States, and resident of the city of Providence, in the county of Providence and State of Rhode Island, have invented certain new and useful Improvements in Machines for Opening Envelops, of which the following is a specification.

This invention relates to machines for opening envelopes and has for its object to provide a machine of this character which is provided with a pair of rotary cutters, and means for feeding envelopes to said cutters whereby a small portion of the edge of the envelop is removed to expose its contents.

A further object of the invention is to provide a pair of feed rolls and a pair of independent guide rolls the latter being located approximately opposite the cutters for engaging, feeding and guiding the envelop while it is being operated upon by said cutters.

A further object of the invention is to set one roll of each pair at an angle to the axis of its mate whereby the envelop is held firmly in position against its guide while being operated upon by the cutter.

The invention further consists in providing a table with a guide flange, and means for adjusting said table and flange longitudinally to regulate the amount that shall be cut from the edge of the envelop.

With these and other objects in view, the invention consists of certain novel features of construction, as will be more fully described and particularly pointed out in the appended claims.

Figure 1—is a perspective view illustrating my improved letter opener coupled to, to be driven by an electric motor. Fig. 2—is a front elevation of the machine with the casing partly broken away and in section to better illustrate the operating mechanism. Fig. 3—is a detail illustrating one of the guide rolls mounted on the pivotally hung gear casing. Fig. 4—is a plan view showing a portion of the casing in section to better illustrate the mechanism. Fig. 5—is a sectional elevation from the left end of the machine showing the relation of the cutters and guide rolls. Fig. 6—is a perspective view of the table in detail. Fig. 7—is a detail illustrating one of the feed rolls as mounted on a pivoted arm.

55 Referring to the drawings, 10 designates

the casing which incloses a portion of the operating mechanism, the same being preferably substantially cylindrical in form and provided with a removable rear portion 11 and this casing is arranged to be supported 60 upon the base portion 12.

A table 13 is arranged to extend across the front of the casing, the same being provided with arms 14 and 15. The arm 14 is preferably rigidly secured to the side of the 65 casing by screws 16—16 while the arm 15 is retained in the desired position by means of screws 17 which pass through longitudinal slots 18 in said arm.

A cam 19 is supported in position on the 70 pivot screw 20 to engage said arm and is provided with a lever 21 having a handle 22 whereby when it is desired to move the table in or out, that is from or toward the cutters, it is only necessary to turn or swing the handle from one position to another for the purpose hereinafter described. The inner edge of this table is turned upward, as at 23, see Figs. 4 and 6, providing a flange 75 which serves as a guide for the envelops in 80 being carried across the table and acted upon by the knives.

A pair of complementary conical cutters 24 and 25 are arranged to meet and overlap each other through the opening 33 in the 85 table, and are mounted on shafts 26 and 27 in bearings 26^a and 27^a respectively, and driven by the intermeshing gears 28 and 29 through the pinion 30 and shaft 31 by the 90 motor 32.

A lower feed roll 34 is mounted on the shaft 35 supported in the fixed bearing 35^a on the arm 44 and is driven from the shaft 27 by the pulleys 36 and 37 and belt 38. An upper feed roll 39 is mounted on the 95 arm 40 and is pivoted at 41 to the bearing support 42, see Fig. 5. An aperture 52 in the table permits the roll 34 to contact with the envelops when fed thereover. This upper feed roll has an axis set on an angle to that of its mate or complementary roll below and is mounted to rotate freely on the pivot screw 43. A tension is applied to this roll by spring 45 so as to bite the envelop between it and the driver 34 to feed the same. 100

It is found in practice that a single set of rolls is not sufficient to feed and guide the envelops accurately through the machine while being operated upon by the cutters, therefore I have provided another set of 105 110

rolls which serve, in addition to assisting in feeding the envelopes, to also guide the same and hold them accurately in position while being operated upon so that a cut of 5 a uniform width will be taken. The lower or driving roll 46 of this set is mounted on and fixed to the end of the cutter shaft 27 and the upper roll 47 of this pair is loosely mounted on the screw 48 which is threaded 10 into the hub 49 on the casing 50, which is designed to cover and protect the upper cutter 24. This casing is pivotally connected to the frame on the screw 51 whereby the same with its roll may raise or lower and accommodate itself to envelopes of different thicknesses. The axis of this upper roll, like 15 that of roll 39, is set on an angle to its supplemental roll or mate, whereby the envelope is carried backward or inward and held 20 against the guide while passing through the machine. The opening 33 in the table is large enough so that in addition to permitting the cutters to meet therethrough the periphery of the roll 46 may extend there- 25 through to engage the underside of the envelope.

In the operation of my improved machine the envelopes α to be opened are placed in a pile on the left end of the table 13 where 30 by a simple movement of the hand of the operator they are advanced and engaged by the feed rolls 34 and 39 and fed forward to be acted upon by the cutters which remove a very small portion or strip of the 35 folded edge of the envelope but not enough to possibly cut into the contents thereof. It is found in practice that with a single set of feed rolls the cut taken through the envelope is apt to be uneven or not uniform, 40 that is, the forward portion of the envelope has a tendency to work outward and in some cases prevent the cutters from cutting the envelope. To obviate this difficulty I have mounted an auxiliary set of rolls opposite 45 the cutters which serve to hold the envelope firmly back against the guide while passing through the machine.

The table on which the envelopes rest is supported on arms 14 and 15 which are more 50 or less resilient or yieldable and when it is desired to obtain a deeper cut or to cut more from the edge of the envelope, the lever 17 is thrown over backward or to the rear of the machine whereby its cam-shaped hub 55 carries the arm 15, and consequently the guide flange 23, backward and causes the arm 14 to spring slightly, thus permitting

a wider edge on the envelope to be presented to the cutters.

I claim:

1. In an envelope opening machine, a supporting table, a pair of rotary cutters, a pair of envelope feeding and guiding rolls mounted substantially opposite said cutters to support the work while being acted upon thereby, and means for rotating said cutters and rolls. 60

2. In an envelope opening machine, a supporting table, a pair of rotary cutters, a pair of envelope feeding and guiding rolls mounted substantially opposite said cutters, to support the work while being acted upon thereby the axis of one of said rolls being set on an angle to that of the other of the pair and means for driving both cutters and one of 75 said rolls. 70

3. In a machine for opening envelopes, a pair of rotary cutters, a set of feed rolls, mounted substantially opposite said cutter, a set of guide rolls, the axis of one of each 80 of said sets of rolls being set on an angle to that of its mate, means for driving both of said cutters and one of said rolls in each set, and a table over which the envelopes to be opened are fed by said rolls. 85

4. In a machine for opening envelopes, a pair of rotary cutters, a set of feed rolls, mounted substantially opposite said cutters, a set of guide rolls, the axis of one of each 90 of said sets of rolls being set on an angle to that of its mate, means for driving both of said rolls in each set, a table over which the envelopes to be opened are fed by said rolls, and means whereby one roll of each set is adjustable to feed letters of different thick- 95 nesses. 85

5. In a machine for opening envelopes, a pair of driven rotary cutters, a pair of feed rolls, mounted substantially opposite said cutters, a pair of independent guide rolls, 100 means for driving one roll of each set, the axis of one of said rolls being set on an angle, a table for supporting the envelopes while being cut, a guide flange on said table back of said cutters, and means for adjusting said table and guide to regulate the amount to be cut. 105

In testimony whereof I affix my signature in presence of two witnesses.

EPHRIAM J. SCOTT.
